UNITED STATES PATENT OFFICE.

LOUIS FISCHER, HUGO BILGRAM, AND CARL FEDDERN, OF PHILADELPHIA, PENNSYLVANIA, ASSIGNORS TO RICHARD H. WRIGHT, OF DURHAM, NORTH CAROLINA.

STAMP APPLYING AND AFFIXING MACHINE.

1,187,295.

Specification of Letters Patent. Patented June 13, 1916.

Application filed November 27, 1914. Serial No. 674,322.

To all whom it may concern:

Be it known that we, LOUIS FISCHER, HUGO BILGRAM, and CARL FEDDERN, citizens of the United States, residing at Philadelphia, in the county of Philadelphia and State of Pennsylvania, have invented new and useful Improvements in Stamp Applying and Affixing Machines, of which the following is a specification.

10 The present invention has for its object to provide a machine for affixing stamps and the like to receptacles and more especially for applying revenue stamps to the tops of cans containing tobacco, the stamps, 15 according to the present invention, being gummed and applied successively to the receptacles, the ends of the stamps being pressed yieldingly against the sides of the receptacles, then brushed to insure adherence thereto, whereupon the receptacles with the gummed stamps thereon enter a wheel or equivalent storage device whereby the gummed stamps are dried to insure permanent adherence, the stamps being applied 20 rapidly and uniformly and the loss of stamps is practically avoided.

To these and other ends, the invention consists in certain improvements, and combinations and arrangements of parts, all as 25 will be hereinafter more fully described, the novel features being pointed out particularly in the claims at the end of the specification.

In the accompanying drawings:—Figure 35 1 is a front elevation of a stamp-affixing machine constructed in accordance with the present invention; Fig. 2 is an elevation of the machine as viewed from the left in Fig. 1; Fig. 3 is a top plan view of the machine 40 as shown in Figs. 1 and 2; Fig. 4 is an enlarged detail view, partly in section, showing the devices for feeding, gumming and applying the stamps to the receptacles, together with the devices for affixing the ends 45 of the stamps to the sides of the receptacles; Figs. 4^a and 4^b are detail views of the slide forming part of the stamp or label feeding means; Figs. 5, 5^a, 6 and 7 are detail views of the mechanism for feeding the 50 cans to the stamp-affixing means, Fig. 5 representing the same in end view, Fig. 5^a being a detail section of the driving gears, Fig. 6 showing the feeding means as viewed from the right in Fig. 5, and Fig. 7 being a

top plan view; Fig. 8 is a detail view showing the operating means for the stamp-affixing devices; Fig. 9 is an elevation of the construction shown in Fig. 8 and as viewed from the left of said figure; Fig. 10 is a top plan view of Fig. 8; Figs. 11-13 inclusive 55 are detail views of the gumming device for the stamps, Fig. 11 showing the same as viewed from one end, Fig. 12 being an elevation of the construction as viewed from the right in Fig. 11, and Fig. 13 being a top 60 plan view of Fig. 12; Figs. 14 and 15 are detail views showing the drying wheel wherein the stamped cans or receptacles are stored until the stamps have been dried, Fig. 14 showing a portion of the wheel in side 65 elevation, and Fig. 15 representing a section taken through the axis thereof; Figs. 16 and 17 are diagrammatic views, in elevation and top plan, respectively, showing the manner in which the stamp is initially fed 70 and applied to the top of a receptacle; Figs. 18 and 19 are diagrammatic views, in side elevation and top plan, respectively, showing the manner in which the ends of the stamp are initially applied to the side edges 75 of the can or receptacle; Figs. 20 and 21 are views similar to Figs. 18 and 19 respectively, showing the manner in which the ends of the stamp are yieldingly pressed upon the curved or convex edges of the receptacle; Fig. 22 is an edge view of the receptacle with the stamp applied as in Figs. 20 and 21; Fig. 23 shows a receptacle with a stamp applied and affixed thereto in the condition in which it leaves the machine; 80 Fig. 24 shows diagrammatically the application of a stamp to a beaded receptacle; Figs. 25 and 26 represent transverse and longitudinal sections respectively of the pockets of the drying wheel showing means 85 for detachably holding the brushes therein.

Similar parts are designated by the same reference characters in the several views.

The present invention in its broadest sense provides a machine for affixing stamps or similar devices, such as labels, to receptacles, and more particularly it provides a machine for rapidly and uniformly affixing revenue stamps to the tops of cans or other receptacles composed of metal or other material and having rounded or convex side edges, the stamps, according to the present invention, being so affixed as to insure per-

manent adherence thereof to the receptacles even when applied to metallic cans.

The accompanying drawings show and this specification will describe in detail a machine for applying and affixing revenue stamps to metallic cans having rounded or convex side edges. It is to be understood, however, that the invention is not restricted to the precise construction shown, as modifications and changes within the scope of the claims can be made in order to adapt the machine to different requirements.

In the present instance the machine comprises a base or table 1 which serves to support the different mechanisms of the machine. The table is mounted on legs 2 and the latter support a driving shaft 3 which may receive its motion from a belt pulley 4 or any other suitable means. The cans or receptacles to which the stamps are to be applied are preferably fed automatically to the stamp-applying and affixing devices. In the construction shown a runway is provided along which the cans are fed while in upright position, this runway comprising a pair of side rails 5 and an endless conveyer belt 6, the latter forming the bottom of the runway and constituting a support on which the cans or receptacles rest. This belt preferably receives constant motion in a direction to advance the cans or receptacles to the stamp-applying and affixing devices, it passing over pulleys 7 and 8 in the present instance, and the pulley 7 receiving constant motion through the gears 9, 10 and 10^a, bevel gearing 11, shaft 12 and bevel gearing 13, the latter being driven from the shaft 3. An abutment 14 is attached to the side rails 5 to arrest the advancing movement of the foremost can or receptacle when the latter reaches a position to be received and acted upon by the stamp-affixing and applying devices. The runway is preferably provided with a bottom plate 15 beneath the upper stretch of the conveyer belt 6 whereby the latter is supported in a manner to sustain the weight of the cans or receptacles resting thereon. Beyond the roll 7, the bottom 15 of the runway is provided with an aperture 16 through which operates a plunger, to be hereinafter described, for lifting the receptacles successively into the devices which apply and affix the stamps.

Means is provided for advancing the receptacles from a position above the roller 7 into a position above the aperture 16 and for insuring correct upright position of the receptacles preparatory to the elevation thereof. In the present instance a pair of fingers 17 are provided, the ends of which are forked to straddle the side rails 5 of the runway and to engage successively in rear of the receptacles. These fingers are pivoted at 18 to a slide 19, the latter being guided to reciprocate on the side rails 5, and

a spring 20 connects the fingers 17 and operates to normally draw them toward one another and into a position to engage the receptacles. The opposite ends of the fingers 17 are provided with rollers 21 adapted to coöperate with relatively fixed cams 22 which are supported on the side rails 5 whereby reciprocating movement of the slide 19 and the fingers will cause the latter to move apart and thereby pass a receptacle in the runway when the fingers are retracted and to move toward one another and engage behind such receptacle and to advance the same when the fingers are advanced. Any suitable means may be provided for reciprocating the slide 19 and the fingers at appropriate intervals. In the present instance, a bell-crank lever 23 is provided, the upper arm of which is connected by a link 24 to the slide 19 and the other arm of which is provided with a roller 25 which coöperates with a cam 26, the latter being loose on a shaft 27 on which one of the bevel gears 11 is mounted. A tension spring 28 operates to hold the roller 25 in coöperative relation with the cam 26.

The devices for applying and affixing the stamps are mounted in alinement above the aperture 16 in the bottom plate 15 of the runway and the stamps are fed to the receptacles from a magazine and stamp-feeding means located at one side of the stamp-affixing and applying devices. In the construction shown, a stamp-containing magazine 29 is provided, the stamps *x* being stacked therein and resting upon a bottom 30. A feeding plate 31 operates through an opening in the bottom 30 and, in the example shown, has a movement similar to that of the presser foot of a sewing machine, that is to say, it moves upwardly and forwardly to feed the lowermost stamp from the stack in the magazine, then moves downwardly and rearwardly preparatory to the feeding of another stamp. Any suitable means may be provided for operating the feeding plate. In the present instance, the feeding plate is pivotally mounted upon an arm 32 of a bell-crank lever, this bell-crank lever being pivoted at 33 on a horizontally reciprocatory friction-held slide 33^a, and is provided with a roller 34 which coöperates with a cam 35, the latter being fixed to a shaft 36. A fork 37 is operatively connected to the bell-crank lever and has a pair of opposed stops 38 which are arranged at opposite sides of a lug 39 on the slide 33^a. As the bell-crank lever is rocked about its pivot 33, the first part of the rocking movement causes the feeding plate 31 to rise and engage the lowermost stamp in the stack, and the further rocking of the bell-crank lever in the same direction causes the bell-crank lever and the feeding plate to move forwardly, thereby feeding a stamp from the bottom of 130

the stack. The reverse rocking of the bell-crank lever causes the feeding plate 31 to descend and then move rearwardly to bring it into position to again rise and feed another stack. The rising and falling movements of the feeding plate are caused by the alternate engagement of the stops 38 with the lug 39. In order to insure the feeding of but one stamp at a time, a needle or pointed projection 40 is preferably provided upon which the rear end of the stack rests. Also to insure correct feeding of the stamps, a weight is preferably provided which exerts pressure upon the stack of stamps during the feeding motion of the plate 31 and which relieves such pressure after each stamp has been fed from the magazine. In the construction shown, a weight 41 is provided which rests upon the top of the stack of stamps, this weight having a rod 42 attached thereto, the rod extending through a guide 43 at the top of the magazine, and a clutch bar 44 is provided which is adapted to rock about an adjustable stop 45 to clutch and unclutch the rod 42 and also to move bodily upwardly to lift the weight 41 and thereby relieve the pressure upon the stack. The necessary movement of the clutch bar 44 is derived from a vertically movable rod 46 which operates in guides 47 and is provided at its lower end with a roller 48 which co-operates with a cam 49, the latter revolving on the shaft 36 and being connected to a sprocket wheel 82 which is driven from the sprocket 84 on the shaft 3. The construction and mode of operation of the weight 41 is described more fully in the patent granted July 27, 1915, to Louis Fischer, No. 1,148,373.

As each stamp is fed from the magazine by the feeding plate 31, it is engaged by a device which completes the withdrawal of the stamp and draws the stamp into a position across the top of the receptacle, this operation taking place while the pressure of the weight 41 is relieved. In the construction shown, a gripper is provided for accomplishing this result, the gripper comprising a slide 50 having relatively movable jaws 51 and 52 adapted to engage the forward end of the stamp between them. A notched arm 53 is connected to one of the gripper jaws, and a detent 54 is arranged to co-operate with the respective notches in said arm to retain the jaws in open position while the gripper is moving into a position to receive a stamp and to retain the jaws in closed position as the gripper is advancing to withdraw the stamp from the magazine and to feed it across the top of the receptacle. The opening and closing of the gripper jaws is effected automatically during the reciprocatory movements of the slide by an arm 55 which is connected to the notched arm 53 and is arranged to engage

and to be operated by projections 56 and 57 as it approaches the limits of its reciprocatory movements.

During the withdrawal of each stamp from the magazine by the gripper, gum or paste is applied to the under side of the stamp and, according to the present invention, pasting or gumming means is provided which insures the application of the gum or paste throughout the length of each stamp. The gumming or pasting means shown comprises a gum or paste reservoir 58 having a gum feeding roll 59 mounted therein and a gum applying roll 60 which receives paste from the roll 59 and applies the paste to the under side of the stamp. The rolls 59 and 60 are revolved in the directions indicated by the arrows by a gear 61 fixed to the shaft of the gum feeding roll 59, this gear 61 being connected through the gears 62 and 63 to a gear 64 which latter gear is connected to the shaft 36 by a ratchet clutch 65. In order to enable the gripper to advance into close proximity to the magazine to engage the forward end of the stamp without interference with the gumming device, the latter is movable vertically whereby it may be lowered when the gripper advances to engage a stamp and may rise to apply paste to the stamp when the gripper is retracted to withdraw the stamp from the magazine. As shown, the gumming device as a whole is mounted on a vertically movable slide 66 which is mounted in a vertical guide 67 secured to a suitable part of the frame of the machine, and the necessary rising and falling movements are imparted to the gumming device at appropriate intervals by a lever 68 which is fulcrumed on the stationary axis 69 and is connected to a bar 70, the lower end of which is provided with a fork 71 which straddles the shaft 3 and is provided with a roller 72 which co-operates with a suitably shaped cam 73 on said shaft. The gumming device applies gum or paste to the entire under side of the stamp, excepting that portion of the stamp which is engaged by the gripper. In order to apply gum or paste to the portion of the stamp engaged by the gripper, an auxiliary gumming device is provided which comprises a gum or paste reservoir 74 having a gum feeding roll 75 mounted to revolve therein and a gum applying roll 76 which co-operates with the roll 75 and operates to apply gum or paste to the forward end of the stamp after the same has been released by the gripper. The shaft 36 reciprocates the gripper slide 50 by a gear 50* which co-operates with rack teeth on said bar, said shaft being rotated alternately in reverse directions by a pinion 77 which is fixed thereon and a rack 78 which co-operates with said pinion, the rack 78 being operated by a bar 79, the lower end of which is forked to

- straddle the shaft 3 as a guide and carries a roller 80 which cooperates with a cam 81, the latter being mounted on the shaft 3. A sprocket wheel 82 is also mounted loosely 5 on the shaft 36 and is connected by a sprocket chain 83 to a sprocket wheel 84, the latter being mounted on the shaft 3, the sprocket wheel 82 being connected to operate the weight controlling cam 35.
- 10 Above the end of the bottom plate 15 of the receptacle feeding device are mounted the devices for affixing the gummed stamps to the receptacles. A guard 85 is mounted immediately above the aperture 16 15 in the bottom plate 15 and is hollow to permit the passage of the receptacle therethrough. This guard occupies an elevated position clear of the path of the stamp as the latter is fed across the top of the receptacle by the gripper, and after the stamp has been so fed the guard descends to insure proper application of the stamp to the receptacle. In the construction shown, the guard is provided with a slide 86 which is 20 movable vertically in guides 87 provided on a stationary frame 88, the guard being raised and lowered by a lever 89 which is pivoted on the frame 88 at 90 and is connected to a link or rod 91, the lower end 25 of which is forked to straddle the shaft 3 and is provided with a roller 92 which cooperates with a cam 93 on said shaft. The guard has out-turned portions 94 and 95 to press the ends of the stamp down- 30 wardly toward the sides of the receptacles, the portion 94 pressing the ends of the stamp previously engaged by the gripper into contact with the gum-applying roll 76 whereby gum is applied to that part of the 35 stamp which was left ungummed by the roll 60. The extension 95 of the guard also preferably has a pair of downwardly directed fingers 96 between which the stamp is passed by the gripper, these fingers serving to guide the stamp and insure the application of the same in a straight line across the top of the receptacle whereby the ends of the stamp will be applied in proper vertical position on the side edges 40 of the receptacle. Above the guard is located a pair of rollers 97 and 98 arranged at opposite sides of the path of the receptacle as the latter is elevated, and these rollers are opposite to the side edges of the 45 receptacle and press the ends of the stamp against the side edges of the receptacle. These rollers are preferably forced yieldingly into engagement with the receptacle, they being movably mounted in bearings 99 and 100 whereby they may approach and 50 separate relatively to one another, and springs 101 and 102 act to force them yieldingly toward one another. The receptacles are successively elevated and thereby re- 55 moved from the runway and passed through the guard 85 and between the rollers 97 and 98 by an elevating plunger 103, the upper end of which has a laterally bent foot 104 which passes vertically through the opening 16 in the bottom plate 15 of the runway. The plunger is reciprocated at appropriate intervals by any suitable means, that shown comprising a lever 105 which is fulcrumed at 106 on a stationary bracket 107, its intermediate portion is provided with a 70 roller 108 which cooperates with a cam 109, and its opposite end is connected at 110 to the lower end of the plunger 103. A shield 111 projects downwardly from the frame 88 and serves to prevent rising of the receptacle adjacent to the one which is engaged by the plunger 103.
- Means is provided above the rollers 97 and 98 to yieldingly press the ends of the stamp into engagement with the sides of the receptacle in order to secure intimate and firm adherence thereto. According to the present invention, a pair of bands 112 and 113 are provided which may be composed of rubber or other pliable or resilient material, these bands being stretched over pins or rollers 114 and 115 so that the intermediate portions of the bands will press against the ends of the stamps, and in the case of cans having convex sides, the 95 ends of the stamps will be bent around the cans or receptacles and thereby assume the same contour. Means is provided for retracting these bands during the introduction of the upper end of a stamped receptacle thereto and for pressing the bands into engagement with the ends of the stamp after the receptacle has assumed a position between them. In the construction shown, the pins or rollers 114 and 115 which support the bands are carried by a pair of arms 116 and 117, these arms being pivoted to the frame 88 by shafts 118 and 119, and said shafts are connected to rotate simultaneously in reverse directions by a 100 pair of gear segments 120 and 121, an arm 122 being connected to one of the gear segments and said arm in turn being connected by a link 123 to an arm 124 of a bell-crank lever, the latter being pivoted to the 115 frame 88 at 125 and having its other arm 126 connected to a rod 127, the lower end of said rod being forked to straddle the shaft 3 and provided with a roller 128 to cooperate with a cam 129 on the shaft 3. 120 Above the bands 112 and 113, means is provided for brushing the ends of the stamp against the sides of the receptacle. In the construction shown, a pair of brushes 130 and 131 are provided, it being 125 preferable to employ bristle brushes which are adjustable toward and from one another to provide a passageway of the proper width between them for the receptacles. Guard rails 132 are also preferably 130

provided to operate with one of the flat faces of each receptacle and thereby guide the same relatively to the brushes. Preferably, the brushes and also the bands 112 and 113 are movable vertically whereby the same may act upon each receptacle while the same is being elevated. To this end, the brushes and also the shafts 118 and 119 supporting the arms 116 and 117 carrying the bands are mounted on a vertically movable slide 133, and said slide is raised and lowered at appropriate intervals by a link 134 connected thereto, a lever 135 connected to said link and pivoted to the frame 88 at 136, and a rod 137 which is connected to the lever 135 and is forked at its lower end to straddle the shaft 3 and provided with a roller 138 which co-operates with a cam 139 on the shaft 3.

26 According to the present invention, means is provided for storing the receptacles after the gummed stamps have been applied and affixed thereto in order to afford an opportunity for the gum to dry and thereby permanently affix the stamps to the receptacles. In the present instance, a pocketed wheel is shown, this wheel comprising a disk 140 mounted to revolve on a supporting shaft 141, the disk being provided on one of its faces with a circumferentially spaced series of radial pockets formed between radial partitions 142 as well as a series of pockets 143 which are located outwardly beyond and in alignment with the pockets between the partitions 142. The pockets 143 are provided with brushes 144 and 145 to co-operate with the ends of the stamp and thereby retain the same in close engagement with the sides of the respective receptacle during the drying or the setting of the gum or paste. These brushes also serve to frictionally retain the receptacles within the pockets during rotation of the wheel. The wheel is rotated step-by-step at appropriate intervals. For this purpose it is provided with a ratchet ring 146 and an arm 147 which is pivoted to swing about the shaft 141 as an axis and is provided with a pawl 148 which co-operates with the ratchet ring. The arm 147 is actuated at suitable intervals by a rod 149 which is connected at its upper end to said arm and is connected at its lower end to the pin of a crank 150, the latter being fixed to one end of the shaft 3. During rotation of the shaft 3, the wheel receives a step-by-step motion which presents the pockets therein successively in alignment with the passage-way formed between the brushes 130 and 131, and the plunger 103 operates during the 50 process of rest of the wheel to introduce a stamped receptacle into the aligned pocket. As a receptacle is introduced into each of the outer pockets 143, the receptacle already in said pocket is lifted into the corresponding pocket between the partitions 142 where- by the wheel will contain receptacles which will completely fill all the outer pockets 143 and will partially fill the inner pockets formed between the partitions 142. In order to prevent premature dropping of the receptacles from the inner pockets, a guard 151 is provided which is located within the circular line defined by the inner ends of the partitions 142. Means is also provided for frictionally retaining the receptacles within the inner pockets until the proper moment for the discharge of such receptacles. As shown, a rail 152 is provided which carries a strip of felt or other yielding material 153 which is arranged to bear upon the sides of the receptacles as the latter are advanced by the rotation of the wheel toward the point of discharge. The receptacles are discharged from the inner pockets into a chute 154, the receptacles dropping by gravity 85 into this chute when they pass the felt strip 153 and the guard 151. The chute 154 conducts the receptacles to a table 155 which is provided with means for stacking the receptacles in convenient condition for packing. In the construction shown, a pair of guides 156 and 157 are arranged on the top of the table, and a continuously moving endless belt 158 travels over the table between the guides 156 and 157 whereby the 90 receptacles are received by the belt from the chute 154 and conveyed across the table. The belt may be driven in any suitable way. In the present instance, it passes over pulleys 159 and 160, the pulley 159 having its 100 shaft connected by bevel gearing 161 to a sprocket wheel 162, and the latter is connected by a chain 163 to a sprocket wheel 164, the latter being fixed to a shaft 165 which shaft is connected to the main shaft 3. 105

In order to enable the stamp-affixing and receptacle-retaining brushes in the drying wheel to be readily removed for cleaning of gum therefrom, or replaced, it is preferable to mount these brushes removably in the 110 pockets. In the present instance, these brushes 144 and 145 have backs 166 which are slidable longitudinally into and out of channels 167 in the ends of each pocket, they abutting against shoulders at their inner 115 ends, as appears in Fig. 15, and they are frictionally held in place by springs 168 which are attached to the walls of the pockets and bear yieldingly against the edges of the brush backs. These brushes not only 120 press the stamp ends around the convex sides of the receptacles and retain them in such condition until the stamp has become dried, but they also brush down the ears or corners of the stamp which are produced 125 by the bending of the stamp over the rounded edges between the top and sides of the receptacle, as appears in Fig. 23.

Figs. 16 and 17 show the manner in which the stamp is fed across the top of the recep- 130

tae by the gripper. Figs. 18 and 19 show diagrammatically the manner in which the rollers 97 and 98 press the ends of the gummed stamp against the sides of the receptacle. Figs. 20, 21 and 22 show the manner in which the bands 112 and 113 press the ends of the gummed stamp around the convex sides of the receptacle. Fig. 23 shows the stamped receptacle as it leaves the machine, the corners of the stamp at the points where it bends down against the sides of the receptacle forming ears which are folded downwardly.

Fig. 24 shows diagrammatically one of the upper corners of a receptacle having a bead surrounding the same immediately below the lid or cover thereof and illustrating the manner in which each end of the stamp or label is pressed by the band 112 or 113 against the respective side of the receptacle and showing how the end of the stamp is pressed or clamped over and into intimate contact with the bead whereby the end of the stamp conforms to the shape of the side of the receptacle.

What is claimed is:—

1. In a machine for affixing stamps to receptacles having elongated tops and opposed convex sides, the combination of means for applying a stamp with its intermediate portion engaging longitudinally the elongated top of the receptacle, and the ends of the stamp engaging the opposed convex sides of the receptacle, ears being formed in the stamp at the corners of the receptacle where the flat top and convex sides meet, and means for bending such ears downwardly toward the bottom and inwardly against the respective convex sides of the receptacle.
2. In a machine of the class described, the combination of means embodying a gripper to engage one end of a stamp and feed the same to a receptacle, means for applying gum to the part of the stamp not engaged by the gripper, means for moving the ends of the stamp toward the sides of the receptacle, and means for applying gum to that part of the stamp previously engaged by the gripper while the respective end of the stamp is moving toward the adjacent side of the receptacle.
3. In a machine of the class described, the combination of a magazine to contain stamps or the like, means for feeding the stamps from the magazine, means embodying a reciprocatory gripper for withdrawing the stamps from the magazine and for drawing the stamps across the tops of receptacles, and gumming means operative on the under side of the stamp about withdrawal thereof, said gumming means being movable to and from operative position to accommodate the gripper.
4. In a machine of the class described, the

combination of means for feeding a stamp to a receptacle, a guard formed with an opening for relative movement of a receptacle therethrough and having at its entrance portions arranged to engage the ends of the stamp and initially bend the same toward the opposite sides of the receptacle as the latter enters the guard, and means for affixing said ends of the stamp to said sides of the receptacles during a continuance of such relative movement.

5. In a machine for affixing stamps to receptacles having elongated flat tops and convex sides, the combination of means for feeding a stamp to a receptacle with the intermediate portion of the stamp in position for application longitudinally to said elongated top, and means relatively movable toward the convex sides of the receptacle and operative to press the ends of the stamp against such convex sides of the receptacle below and immediately adjacent to the top of the receptacle.

6. In a machine for affixing stamps to the lids and sides of receptacles, the combination of means for feeding a stamp to a receptacle with the intermediate portion of the stamp in position for application across the lid of the receptacle, and means to press the ends of the stamp against the convex sides close under the top of the receptacle embodying resilient bands having means for moving them to and from operative position at opposite sides of the receptacle.

7. In a machine for affixing stamps to the lids and convex sides of receptacles, the combination of means for feeding a stamp to a receptacle with the intermediate portion of the stamp in position for application across the lid of the receptacle, and a pair of yielding members operative at opposite sides of the receptacle to press the ends of the stamp upon said convex sides at points below and immediately adjacent to the top of the receptacle, forming projecting ears in the stamp at the corner of the receptacle.

8. In a machine for affixing stamps to receptacles having elongated flat tops and convex sides, the combination of means for feeding a stamp to a receptacle with the intermediate portion of the stamp in position for application to said flat top, and brushes between which the receptacle with the stamp thereon is adapted to pass, said brushes being operative to bend down the ears resulting from pressing the ends of the stamp upon the convex sides of the receptacle, and holding the ends in position pending the drying of the paste.

9. In a machine of the class described, the combination of means for feeding a stamp across the top of a receptacle, a guard for directing the ends of the stamp toward the

- sides of the receptacle, rollers operative to initially press the ends of the stamp against the sides of the receptacle, yielding members for further pressing the ends of the stamp 65
 5 against the sides close under the top of the receptacle, and brushes for holding the ends of the stamp to the sides of the receptacle.
10. In a machine of the class described, the combination of means for applying and 10 affixing stamps by adhesive successively to receptacles with the ends of the stamps engaging the sides of the receptacles, and means forming a passageway for the receptacles and presenting pressure surfaces to 15 engage and hold the ends of the stamps pressed in affixed relation to the sides of a plurality of the receptacles in such passageway for a period of time sufficient to insure permanent adherence of the stamps.
20. 11. In a machine of the class described, the combination of means for applying stamps by adhesive successively to receptacles with the ends of the stamps engaging the sides of the receptacles, means providing 25 a receptacle receiving pocket having at the opposite sides thereof yielding pressure surfaces to hold the ends of the stamps pressed in affixed relation to the sides of the respective receptacles, and means for advancing the receptacles through said pocket and between said pressure surfaces.
12. In a machine of the class described, the combination of means for applying and affixing stamps by adhesive successively to 30 receptacles, and a device having pockets each operative to successively receive a stamped receptacle, hold the same with the stamp pressed in affixed relation thereto, and to discharge another stamped receptacle.
35. 13. In a machine of the class described, the combination of means for applying and affixing stamps by adhesive successively to receptacles, a rotatable wheel having a circular series of pockets each containing 35 means for retaining the ends of the stamps on a plurality of receptacles pressed in affixed relation thereto, means for rotating the wheel step-by-step to successively receive the stamped receptacles, and means for 40 receiving the stamped receptacles as they discharge from the wheel.
45. 14. In a machine of the class described, the combination of means for applying and affixing gummed stamps successively to receptacles, a rotatable wheel having a plurality of series of radially aligned pockets, one series of pockets containing means for retaining the ends of the stamps in affixed relation to the receptacles, means for rotating the wheel step-by-step to receive the stamped receptacles successively in one series and to cause transfer of the receptacles from such series of pockets to another series of pockets, means for receiving the stamped 50
- receptacles as they are discharged from the wheel, and a guard arranged adjacent to the point of discharge of the receptacles to retain the same in the wheel. 65
55. 15. In a machine of the class described, the combination with means for applying and affixing a gummed stamp to the top and sides of a receptacle, of a stamp-drying member having a pocket to receive the stamp-bearing receptacle, and brushes removably mounted in said pocket and operative to press the ends of the gummed stamp against the sides of the receptacle. 70
60. 16. In a machine of the class described, the combination with means for applying and affixing a gummed stamp to the top and sides of a receptacle, of a stamp-drying member having a pocket to receive the stamp-bearing receptacle, and brushes slidably mounted in opposite sides of said pocket and operative to press the ends of the 75 gummed stamp against the sides of the receptacle, and springs frictionally retaining said brushes in operative position.
65. 17. In a machine of the class described, the combination with means for applying and affixing a stamp by adhesive to a receptacle having a flat top and rounded sides, ears being formed in the stamp at the corners between the top and sides of the receptacle, of means for folding such ears down 80 toward the respective sides of the receptacle. 85
70. 18. In a machine for affixing stamps or labels to metal receptacles having flat lids and opposed convex sides, means for pressing the ends of a stamp or label against the opposite sides of a receptacle immediately below the top of the lid, forming ears in the corner of the stamp, and means for bending such ears toward the respective convex sides of the receptacle. 90
75. 19. In a machine for affixing a stamp or label to a receptacle having convex sides with a bead near the top thereof with the intermediate portion of the stamp extending across the top and the ends thereof in position for application to the sides of the receptacle, opposed members operative to press the ends of the stamps or label against the opposite sides of such receptacle at points immediately below the top of the receptacle, 100 thus forming ears in the stamp, said members having portions opposite to said bead and operative to press the ends of the stamp or label against said bead and thereby cause the same to adhere and conform to the shape 105 of such bead. 110
80. 20. In a machine for affixing stamps or labels to receptacles having elongated lids and opposite convex sides, means for pressing the ends of a stamp or label against the opposite convex sides of such a receptacle, causing such stamp or label to conform to 115 the shape thereof and forming ears in the 120

bent corners of the stamp, and means for bending such ears toward the edges of the respective convex sides of the receptacle.

21. In a machine for affixing stamps to receptacles having elongated lids, the combination with means for applying a stamp across the top of a receptacle with the intermediate portion of the stamp in position for application longitudinally to said elongated lid, a pair of rollers operative to yieldably press the ends of the stamp against opposite sides of the receptacle during relative movement between the receptacle and said rollers, and brushes operative to affix the ends 15 of the stamp against the sides of the receptacle.

22. In a machine for affixing stamps to receptacles having elongated tops, the combination of means for applying a stamp 20 across the top of a receptacle with the intermediate portion of the stamp in position for application longitudinally to said elongated top and the ends of the stamp projecting from opposite sides thereof, means 25 for applying adhesive to such projecting ends of the stamp and means for bending such ends of the stamp with the adhesive thereon against the sides of the receptacle.

23. In a machine for applying stamps to receptacles having elongated tops and opposed convex sides, the combination of 30 means for applying a stamp to the top of the receptacle whereby the intermediate portion of the stamp extends longitudinally of 35 the elongated top of the receptacle and the

ends of the stamp engage the respective opposed convex sides of the receptacle, ears being formed in the bends of the stamp, and brushes arranged to bend such ears downwardly toward the bottom and inwardly against the sides of the receptacle. 40

24. In a machine for affixing stamps to receptacles having elongated tops and opposed convex sides, the combination of means for applying a stamp to a receptacle 45 with the intermediate portion of the stamp engaging longitudinally the elongated top of the receptacle, rollers having opposed peripheries operative on the ends of the stamp to affix them to the respective convex 50 sides of the receptacle, means for pressing the portions of the stamp immediately below the top of the receptacle inwardly, forming creased ears at such points, and means for bending such ears against the 55 body of the receptacle.

In testimony whereof we have hereunto set our hands in the presence of two subscribing witnesses,

LOUIS FISCHER,
HUGO BILGRAM,
CARL FEDDERN.

Witnesses to the signature of Louis Fischer:

E. L. BRACY,
G. A. FOERIN.

Witnesses to the signatures of Hugo Bilgram and Carl Feddern:

MORTIMER A. JONES,
HENRY R. JOHNSON.
